UNITED STATES PATENT OFFICE

151,508

DESIGN FOR A SEWING RACK

James V. Dente, Staten Island, N. Y.

Application January 17, 1947, Serial No. 136,203

Term of patent 7 years

(Cl. D3—19)

To all whom it may concern:

Be it known that James V. Dente, a citizen of the United States of America, residing at Staten Island, in the county of Richmond and State of New York, has invented a new, original, and ornamental Design for a Sewing Rack, of which the following is a specification, reference being had to the accompanying drawing, forming part thereof.

Figure 1 is a perspective view of the sewing rack embodying my new design.

Figure 2 is a front view thereof.

Figure 3 is a side view thereof.

I claim:

The ornamental design for a sewing rack, as shown.

JAMES V. DENTE.
